UNITED STATES PATENT OFFICE.

WALTER J. ANDERSON, OF GALVESTON, TEXAS.

TOUCH-SYSTEM HAND-REST.

1,277,169.

Specification of Letters Patent. Patented Aug. 27, 1918.

Application filed February 2, 1918. Serial No. 215,076.

To all whom it may concern:

Be it known that I, WALTER J. ANDERSON, a citizen of the United States, residing at Galveston, in the county of Galveston and 5 State of Texas, have invented certain new and useful Improvements in Touch-System Hand-Rests, of which the following is a specification.

My invention relates to touch system hand 10 rests for use with typewriter described in Patent No. 1,247,065 granted to me November 20th, 1917.

My present invention is designed to improve the construction of the hand rest and 15 provide novel clamps for attaching the rest to the frame of the typewriter or to a table or typewriter desk, the said clamps to be adjusted and thus adapted to fit the frames of various typewriters, or if desired, fas- 20 tened to a typewriter table or desk.

My invention is also designed to provide such clamps with means for vertically adjusting the height of the hand-rest relative to the key-board, the object being to accommodate the difference in reach between a 25 long and short fingered operator and thus perfect the ease and touch.

Again, said clamps are so designed that provision is made for pivoting the hand-rest in said clamps, whereby they may be swung back over the key-board, when it is desired to place the cover over the machine.

In the accompanying drawing, forming a part of this specification, Figure 1 is a front 30 elevation of a typewriter showing my touch system hand rests attached to the frame of the machine by means of my clamps. Fig. 2 is a side elevation of one of my hand rests as applied to the front bar of a typewriting 35 machine, and Fig. 3 is a top-plan view of the same. Figs. 4 and 5 are detailed sectional views of my clamps taken in lines 4—4 and 5—5 of Figs. 3 and 2 respectively.

Referring more particularly to the drawing 40 A denotes the key-board of a typewriter and a denotes the front bar of the typewriter frame. B B denotes the right and left hand hand-rest. C C denotes my clamps for attaching said hand-rest to the 45 front bar of a typewriter frame, and said clamps are so designed that they may be attached as well to the edge of a table or typewriter desk and serve to adjustably support the hand-rest in front of the key-board of 50 the typewriter.

As shown in the drawings, the main por-

tion of each hand-rest is curved inwardly as shown in my patent referred to above, but in my present invention, I make the lower part or base b of the rests broader, the inner edges 60 being arc-shape as shown in Fig. 3, thereby affording a more comfortable support for the wrist or hand, while the arc-shaped edges afford greater range of play for the fingers of the operator. Depending from 65 this base and made integral therewith is a vertical arm b¹ round in contour.

The clamps C C are formed with cylindrical openings which register with and through which the arms b¹ b¹ pass and are 70 adapted to slide vertically therein, whereby the height of the hand-rest relative to the key-board may be adjusted. To hold the hand-rest in adjusted positions, I provide the clamps with set-screws c c as shown in 75 Figs. 1, 3, and 5. As shown in Fig. 4 the face of the clamps is provided with ratchet teeth c¹, and the lower end of the clamps is formed with a jaw c² upwardly inclined. Opposed to jaws c², I provide a movable jaw 80 c³ shown in Figs. 2, 3, 4, and 5, which is vertically adjustable, its upper edge engaging the ratchet teeth c¹. c⁴ denotes a lip on jaw c³ provided with a threaded opening which registers with an adjustable set-screw clamp 85 c⁵ designed to draw the contacting edge of the jaw c³ in contact with the ratchet teeth c¹. c⁶ denotes a vertically movable plate formed with a lug c⁷ which rides in a guide channel formed in the back of the clamps as shown 90 in Fig. 5.

In order to attach my hand-rest to a typewriter, or the edge of a table, or typewriter desk, the lower jaws of the clamps are brought to bear on the under side of the 95 front bar of the typewriter frame, or edge of a table, or desk, as the case may be. The opposing jaw of the clamps is then drawn down by hand to bear upon the upper side of said bar or edge; the set screw clamp is 100 then operated to force the upper edge of the movable jaw c³ in biting contact with the ratchet teeth and hold said jaw in place. Both jaws are made wide to adapt them for clamping the edge of a table or desk should 105 it be desired to attach the clamps to a table or desk.

To adjust the hand-rest vertically to the proper height, relative to the key-board, the depending rods b¹ b¹ are adjusted vertically 110 in the cylindrical openings in the clamps until the bases of the rests are in the same

horizontal plane with the second row of keys of the typewriter key-board. To hold the rests in the adjusted position, the set screws *c c* are then set in position to hold the rods 5 in the adjusted position. When it is desired to swing the hand-rests over the key-board of the typewriter the set screws *c c* are loosened from pressure on the arms *b¹ b¹* and the rests may then be turned back over the 10 key-board. With the hand-rests in this position they do not interfere with placing the cover over the typewriter.

It will be evident that my touch-system hand-rest is especially valuable for those 15 learning to typewrite.

Having thus shown my invention, what I claim and desire to secure by Letters Patent, is:

1. A hand-rest for typewriters adapted to 20 be mounted to the typewriter frame, desk, or table in juxtaposition to the key-board of a typewriter, consisting of a suitable hand, or wrist-support provided with a depending arm, a clamping member having a cylindrical opening therein adapted to receive and afford a vertically adjustable bearing for 25

said arm, means for holding said arm in adjusted position, a stationary jaw and a movable toothed jaw adapted to clamp a type-writer frame, desk, or table, ratchet 30 teeth adapted to engage said toothed-jaw, and means for holding said jaw engaged.

2. A hand-rest for typewriters comprising means in common for pivotally mounting and vertically adjusting said hand rest in 35 front of the key-board of a typewriter whereby said rest may be adjusted vertically relative to the key-board or swung horizontally thereover.

3. A hand-rest for typewriters of 40 concaved shape, the base of the rest being broadened and having an arc-shaped inner edge, a vertically depending arm, and a clamp adapted to be attached to a type-writer frame, desk, or table, having a vertical cylindrical bearing adapted to pivotally 45 mount and vertically adjust said arm, and means for holding said arm in adjusted position.

In testimony whereof I affix my signature. 50

WALTER J. ANDERSON.
